PRODUCTION OF HYDROCARBONS FROM OIL SHALE

Filed Nov. 18, 1924

UNITED STATES PATENT OFFICE

AUGUST P. BJRREGAARD, OF OKMULGEE, OKLAHOMA, ASSIGNOR TO DOHERTY RESEARCH COMPANY, OF NEW YORK, N. Y., A CORPORATION OF DELAWARE

PRODUCTION OF HYDROCARBONS FROM OIL SHALE

Application filed November 18, 1924. Serial No. 750,574.

The present invention relates to the production of hydrocarbons from oil shale.

One of the objects of the present invention is to provide a process for retorting oil shale having a high efficiency, and requiring relatively inexpensive apparatus.

Another object of the present invention is to provide a process for obtaining a high percentage hydrocarbon yield from oil shale at a comparatively low cost.

The novel features of the present invention are pointed out with particularity in the appended claim. The invention itself however with further objects and advantages thereof will best be understood from the following description taken in connection with the accompanying drawing, in which

The figure is an elevation diagrammatic in character, of an apparatus adapted to operate according to the process of the present invention, parts being shown in section and parts being broken away for purposes of illustration.

In the drawing 10 is a hopper for receiving oil shale to be treated, shale supplied to hopper 10 having been previously treated to produce suitable sizes. The shale passes downwardly from hopper 10 through a chute 12, the rate of feed from the hopper being regulated by a valve 14 or other suitable feeding mechanism as desired. As illustrated, chute 12 is arranged vertically and the lower end thereof delivers into an inclined chute 16 arranged to deliver the shale into the upper end of an inclined rotary lagged retort 18. The oil shale is fed forwardly and downwardly through the retort 18 and while it is in the retort it is

treated with a countercurrent stream of hot producer gas. The producer gas for treating the shale in retort 18 is introduced into the lower end of the retort; that is to say, the end opposite the chute 16, the shale which has been longest in the retort 18 thus coming in contact with the hottest gas and the shale just entering retort 18 from the chute 16 encountering the coolest gas.

According to the present invention, no heat is supplied to the exterior of the retort

18, and no heat is supplied to the shale in retort 18 except by the producer gas flowing through the interior of the retort so that the shale in retort 18 is brought gradually to the point at which decomposition of the hydrocarbons in the shale is produced. Moreover, owing to the agitation of the shale in the rotary retort and the fact that heat is supplied to the shale solely by the hot gases, the stream of shale is heated very uniformly. The temperature of the zone in the retort 18 in which the hydrocarbons are given off is fixed and controlled by the temperature of the retort gases, the rate of feed of the shale, and the degree of insulation of the retort 18 against a loss of heat. Owing to the conditions just mentioned, there is practically no chance for any of the shale to become heated to the point at which the hydrocarbons given off by the shale are cracked as they are given off. Moreover, the hot producer gases have a high absorptive capacity for the hydrocarbon vapors and gases and greedily absorb them, and sweep them from the point where they are formed toward the cooler portions of the retort. There is therefore no opportunity for hydrocarbons once freed from the shale to be subjected to secondary cracking. On account of this absence of cracking in the apparatus and process according to the present invention, a maximum yield of liquid hydrocarbon and minimum gas yield is obtained. Moreover, the hydrocarbons obtained under the conditions described have a high degree of unsaturation, a feature not desired by many workers in this art, but which the present applicant deems a favorable one.

The gases entering the lower end of retort 18 are sufficiently hot to drive off all the hydrocarbon material from the shale capable of forming the liquid and more desirable hydrocarbons. The shale leaving the retort 18 consequently is a spent shale in one sense, but contains a considerable amount of solid carbon together with some nitrogen. The apparatus according to the present invention is therefore so arranged that the retort 18 delivers the shale treated

therein into a vertical stationary gas producer 20. It is immaterial to the present invention what type of gas producer is used for receiving the shale from retort 18, but it has been found convenient that a producer be used having the proportions illustrated in the drawing; that is to say, one having a fuel bed 22 of considerable height above which is a gas space 24 opening into the lower end of the retort 18. At the lower end of the producer 20 there is illustrated an ash plate 26, and a ram 28 applied by a power cylinder 30 for removing thoroughly spent shale from the lower end of the producer 20. However, the present invention is not limited to any particular type of devices for removing ash or spent shale from the producer.

Air for maintaining restricted combustion in the producer 20 and for the formation of producer gas therein is supplied through the lower wall of the producer 20 by a pipe 32 passed through said wall. According to the present invention, the air for this purpose is preferably preheated in regenerative furnaces 34, 34. Preferably steam is supplied through furnaces 34, 34 and pipe 32 at the same time with the air in order to assist in the formation of producer gas and to increase the production of ammonia in the producer 20, the ammonia vapor being carried along with the producer gases through the retort 18.

The gases and vapors which pass through the retort 18 comprise the producer gas formed in the producer 20, the hydrocarbons distilled from the shale in the retort 18, and the ammonia distilled from the shale in the producer 20. All of these gases and vapors leave the retort through the chute 16, and thence pass through a pipe 36 to a condenser coil 38.

Condensates and uncondensed gases pass from condenser coil 38 through pipe 40 to condensate tank 42. Liquid hydrocarbons separating out in tank 42 are removed to storage through pipe 44. Uncondensed hydrocarbon vapors, ammonia vapor, and fixed gases pass out of the tank 42 through the pipe 46 and thence to an ammonia scrubber 48. Ammonia liquor is removed from the bottom of the tank 48 through pipe 50. Light hydrocarbon vapors and fixed gases leave the tank 48 through pipe 52 and pass thence to an oil scrubber 54, in which the vapors and gases are scrubbed by a heavy wash oil for the recovery of light hydrocarbon vapors.

The scrub oil and the light hydrocarbons contained therein are removed from the bottom of scrubber 54 by pipe 56. Fixed gas leaves the scrubber 54 by pipe 58 and passes thence through one or the other of branch pipes 60, 60 through the lower wall of one or the other of the regenerative furnaces 34 previously mentioned, according to which one is being heated at the time. The gas coming

through pipe 58 carries a considerable portion of combustible material and this is burned in the regenerative furnaces 34 by means of air supplied through pipes 62, 62 the products of combustion passing in contact with checker work 64, 64 within the furnaces 34. While combustion is being maintained in one of the furnaces 34, the hot products of combustion pass upwardly through checker-work 64, thus heating the checker work, and pass out through one of the valved pipes 66, 66. At the same time air passes through the other furnace 34 to be preheated and the heated air then passes through the pipe 32 into the producer, pipe 32 leading from the upper portions of the furnaces 34. The checker work in furnaces 34 is heated alternately and the combustible gas from pipe 58 is diverted by means of valves 68, 68 in pipes 60 to the other furnace 34 and the air entering the highly heated furnace is passed thence through one of the valved pipes 70, 70 into pipe 32 and thence to the producer 20. Steam, if it is desired to use it in the producer 20, may be introduced through valved pipes 72, 72, which pass through elbows in the pipes 60, 60 previously mentioned. Moreover, a fan 74 may be used to force the air through the checker work in furnaces 34 and through the fuel bed 22. It will be understood, of course, that in operation the valves in the pipes 60, 62, 66 and 70 will be turned by the operators to force the air and gas streams to take the desired courses as described above. Also, while these various valves are illustrated merely as hand valves, they may be any of the approved types of hand or automatically operated valves.

In general, more combustible gas will be made than will be needed in the regenerator furnaces 34 and this excess gas may be led off through pipe 76 for use outside of the system herein described.

It will be seen that in operating according to the present invention, the sensible heat of the gas from the producer itself is sufficient to drive off all the liquefiable hydrocarbons from the oil shale and that no gas or other fuel need be burned for this purpose, aside from the carbon in the shale which is gasified in producer 20. Moreover, unless the shale is below the average in richness an excess gas is produced which may be used for operating gas engines or in furnaces as desired.

It is emphasized that, according to the present invention, no heat is supplied to the rotary retort except the sensible heat of the producer gases. The heating of the shale is thus very uniform and gradual, and much more so than if heat were supplied to the shale through the shell of the retort. In particular, supplying the entire heat of retorting by the gases insures that the gases have a maximum temperature as compared to the shale and hence a maximum capacity to take up and carry off hydrocarbon vapors.

Having thus described my invention, I
claim:

A process of treating oil shale comprising
distilling oil shale in an agitated condition by
5 passing a heated gas into direct contact with
the shale, discharging the distilled shale into
a producer, treating the distilled shale with
preheated air to form the said heated gas,
10 condensing vapors from the gas used for dis-
tillation, and burning the uncondensed gas
from the condenser in a regenerator for pre-
heating the air used in the producer.

In testimony whereof I affix my signature.
AUGUST P. BJERREGAARD.
